CLAIM

The ornamental design for a barbecue tool, as shown and described.

DESCRIPTION

FIG. 1 is a perspective view of a barbecue tool showing my new design;

FIG. 2 is a left side elevational view thereof;

FIG. 3 is a right side elevational view thereof;

FIG. 4 is a front elevational view thereof;

FIG. 5 is the opposite side view of the handle on the left side of FIG. 4 shown separately for the clarity of illustration, the opposite side of the handle on the right side of FIG. 4 being a mirror image thereof;

FIG. 6 is a top plan view thereof;

FIG. 7 is a bottom view thereof; and,

FIG. 8 is the top view of the handle on the left side of FIG. 4 shown separately for the clarity of illustration, the top view of the handle on the right side of FIG. 4 being a mirror image thereof.

The broken lines are for illustrative purposes only and form no part of the claimed design.
